UNITED STATES PATENT OFFICE.

CHARLES NEUBERT, JR., OF BALTIMORE, MARYLAND.

CAN-CLOSURE MACHINE.

Application filed February 9, 1924. Serial No. 691,729.

To all whom it may concern:

Be it known that I, CHARLES NEUBERT, Jr., a citizen of the United States, residing at Baltimore, in the State of the Maryland, have invented certain new and useful improvements in Can-Closure Machines; and I do hereby declare the following to be a full, clear, and exact description of the invention, such as will enable others skilled in the art to which it appertains to make and use the same.

My invention relates to can closure machines.

Among the objects of my invention are:

15 To produce a machine for pressing a closure in a can.

To produce a machine for securing a closure within a can in such a manner that the closure is secured against inadvertent 20 displacement during transportation, but yet can be removed from the can by the ultimate consumer and again replaced therein, if desired.

To produce a machine for pressing and securing a closure within a can in the foregoing manner.

These and further objects of my invention will be set forth in the following specification, reference being had to the accompanying drawings, and the novel means by which said objects are effectuated will be definitely pointed out in the claims.

In the drawings:

Figure 1 is a side elevation of my improved machine, partly in section, showing a can in position to receive its closure.

Fig. 2 is a view of a portion of my improved machine looking in the direction of the arrow 2 in Fig. 1.

Fig. 3 is a section along the line 3—3 in Fig. 2 looking in the direction of the arrows, but showing a closure applying and securing mechanism in contact with the top of a can.

Fig. 4 is a section along the line 4—4 in Fig. 3 looking in the direction of the arrows.

Fig. 5 is a section of certain parts to which reference is hereinafter made.

In the drawings:

10 represents a can table supported in any approved manner by any desired number of legs such as 11 and having secured to its upper surface a guide rail 12 for positioning a can 13 with reference to the closure applying and securing mecha-

nism hereinafter described. Mounted in any approved manner beneath said table is a bracket 14 to which is pivotally secured a foot lever 15. A foot plate 16 is mounted on one end of said lever and at its opposite end a weight 17 is secured for a purpose hereinafter explained.

A rod 18 is pivotally secured to the lever 15 adjacent the weight 17 and extends upwardly through a tube 19, the lower end of which is mounted within the bracket 14. Said tube extends upwardly through a hole 20 provided in the table 10 and has mounted on its upper end the bracket 21. A lever 22 is pivotally mounted on the bracket 21 and one end of said lever registers with the hole at the upper end of the tube 19 and is pivotally secured to the upper end of the rod 18 which passes therethrough. The other end of the lever 22 is pivotally secured to a link 23, the opposite end of which is pivotally secured to a tube 24. Said tube passes through a bracket 25 which is slidably mounted on the tube 19, the tube 24 being locked with reference to the bracket 25 by set screws 26. The bracket 21 also serves as a stop for the bracket 25.

The tube 24 extends downwardly and has mounted on its lower end a flanged collar 27. Resting on the top surface of the collar 27 is a casing 28 which is provided with an upper cylindrical portion 29 through which the tube 24 passes and which serves as a guide for said tube.

The casing 28 is maintained in position on the top surface of the collar 27 by a spring 30 which embraces the cylindrical portion 29 and is interposed between the lower side of the bracket 25 and a boss 31 formed on the casing 28.

The casing 28 is provided with a frustro-conical shaped portion 32 at its lower end and a plate 33 is secured thereto. The casing 28 is further provided with a plurality of shoulders such as 34 and with a plurality of openings 34a in the frustro-conical portion 32 each of which registers with a finger 37 for a purpose hereinafter explained.

The flange 35 of the collar 27 is provided with a plurality of pairs of ears such as 36 and between each pair of said ears one end of a finger 37 is pivotally mounted, the other end of said fingers being provided with toes 38 which normally rest on the top

surface of the plate 33 by reason of the fact that the pivoted ends of the fingers 37 are above said surface, as shown in Fig. 3.

My improved machine is constructed with especial reference to placing a closure in a can constructed as shown in Fig 5, wherein 5 39 represents the body of a can provided with a top 40 having an inwardly disposed flange 41, said flange being circular in the 10 can shown in the drawings, but it is obvious that the flange 41 may be of any desired shape.

42 is a closure having a collar 43 which fits closely within the flange 41.

The operation of my improved machine is 15 as follows:

The operator places a can 13 on the table 10 and said can is positioned for the reception of the can closure by reason of the guide rail 12. A closure 42 is then placed on the 20 top of said can so as to register with its opening, after which pressure is applied to the foot plate 16, and by reason of the interaction of the intermediate parts the bracket 25 operating through the spring 30 forces 25 the casing 28 downwardly so as to contact with the closure 42, thus pressing said closure into the opening of the can, the frustroconical shaped lower portion of the casing 28 assisting in centering said casing with 30 reference to said closure.

When the closure has been fully entered into the can, the under surfaces of the shoulders 34 contact with the crimped edge 13^a of the can 13, preventing further downward displacement of the casing 28. However, the bracket 25 may still move by reason of its resilient connection with the casing 28 and, therefore, the tube 24 which is locked 35 with reference to the bracket 25 will move 40 also. Hence, the pivoted ends of the fingers 37 will move vertically downwardly, thus pressing the toes of said fingers outwardly through the openings 34^a to contact with the collar 43 of the closure 42, as shown in 45 Fig. 5.

The pressure of the toes 38 against the collar 43 will form a series of projections such as 44 thereon as shown in Fig. 5.

When the operator releases the pressure 50 on the plate 16, the spring 30 will raise the bracket 25 upwardly, thus withdrawing the toes 38 from contact with the closure 42 after which the weight 17 operating through 55 the intermediate parts will withdraw the casing 28 from within said closure.

It is obvious that the projections 44 will 60 resist the removal of the closure 42, but that by reason of the inclined upper surface of said projections when the requisite force is applied to the flange 45 of the closure, the upper surfaces of the projections 44 will 65 force the abutting portion of the flange 41 outwardly sufficiently to prevent the removal from the closure 42. When the closure 42 is again placed within the flange,

a nose 46 at the bottom thereof forces the adjacent portion of the flange 41 outwardly to permit the introduction of the closure 42.

It is to be noted that my machine may be used solely for the purpose of placing tops 70 within cans merely by removing the fingers 37, or the tops may be placed therein by hand and my machine used merely for the purpose of securing said tops within said cans, or it may be used for a combination of 75 these two functions.

I have shown my improved machine as applied to a cylindrical can provided with a closure having a cylindrical body portion, 80 but it is obvious that machines may be constructed according to my invention suitable for cans and closures of various shapes.

I have shown one preferred form of my invention, but it is to be understood that the disclosure is for the purpose of illustration 85 only and in nowise to limit my invention to the exact elements and combinations thereof shown, for many changes may be made in the same without departing from the spirit 90 of my invention.

I claim:—

1. In a machine for securing closures in cans, the combination with a casing provided with a portion adapted to fit within said closure, of a collar slidably mounted in said casing and fingers movably mounted on said collar adapted to move outwardly to form projections on said closure during the sliding movement of said collar.

2. In a machine for securing closures in cans, the combination with a casing provided with a portion adapted to fit within said closure, of means slidably mounted in said casing, fingers pivotally secured at one end to said means and provided with toes at the opposite ends, and means for moving said slidably mounted means with reference to said casing, whereby said toes move outwardly to form projections on said closure for coacting with a portion of said can.

3. In a machine for securing closures in cans, the combination with a casing provided with a portion adapted to fit within said closure, of a tube slidably mounted in said casing, a collar secured to one end of said tube, fingers pivotally secured at one end to said collar and provided with toes at their opposite ends, an arm secured to the other end of said tube, a spring interposed between said casing and arm, and means for moving said arm against the resistance of said spring when said casing is resting upon said can, whereby said toes are pressed against said closure to form projections thereon for coacting with a portion of said can.

4. In a machine for securing closures in cans, the combination with a casing provided with a portion adapted to fit within said closure, of a collar slidably mounted in

said casing and fingers, pivotally secured to said collar, adapted to move outwardly to form projections on said closure, said fingers being guided by said casing during said 5 movement.

5. In a machine for securing closures in cans, the combination with a casing provided with a portion adapted to fit within said closure, of a collar slidably mounted in

said casing, fingers pivotally secured to said 10 collar and adapted to move outwardly to form projections on said closure, and means for retracting said fingers to their normal position.

In testimony whereof I affix my signature.

CHARLES NEUBERT, JR.
